COLLAPSIBLE COMBINATION SCREEN
AND TABLE

Ronald E. Ross, Long Island City, N. Y.

Application September 3, 1948, Serial No. 47,619

5 Claims. (Cl. 311—89)

1

This invention relates to a combination screen and table structure. More particularly, the invention deals with an article of furniture of the character described wherein a screen having a series of hinged or folded sections can be quickly and easily converted into a table, the top of which may comprise the area of, or part of the screen sections.

The novel features of the invention will be best understood from the following description when taken together with the accompanying drawings, in which certain embodiments of the invention are disclosed, and in which the separate parts are designated by suitable reference characters in each of the views, and in which:

Fig. 1 is a perspective view of a screen made according to my invention, in set-up condition.

Fig. 2 is a perspective view of the table formed from the screen, shown in Fig. 1.

Fig. 3 is a plan view of the screen showing a covering completely removed on one section and partly removed on the other section, with leg and brace members in collapsed position in the screen section.

Fig. 4 is a perspective detailed view of one corner portion of the table when in set-up condition.

Fig. 5 is a perspective view of another corner portion of the table as in set-up condition.

Fig. 6 is a section on the line 6—6 of Fig. 4.

Fig. 7 is a section on the line 7—7 of Fig. 4, with a part in a different position.

Fig. 8 is a view similar to Fig. 1, with part of the construction broken away and showing a modification; and

Fig. 9 is an end view of a table formed from the screen, as seen in Fig. 3.

In homes or dwellings where space is an important and limited factor, difficulty has been experienced for providing a utility or service table which can be used for any desired purpose. In satisfying this much needed want, I have provided, as part of a screen construction, means for converting a screen into a table, whereby the article of furniture can be utilized in the home as a screen, thus providing a useful article, or the screen can be compactly folded and stored away in a relatively small space.

In Figs. 1 to 3 inclusive, I have shown one form of screen table construction. This structure comprises two substantially similar end screen sections 10 and 11, and an intermediate section 12. The end sections 10 and 11 are hingedly coupled to the intermediate section 12, as indicated, for example, at 13. The intermediate section com-

prises a rectangular frame 14 covered in any suitable manner on both surfaces and braced centrally by a brace member 15. The sections 10 and 11 also comprise rectangular frames 16 and 17, respectively. The frames 16 and 17 will also have facings, but the facings on one side of these frames will be detachable by the provision of suitable snap fastener devices on the frames, as indicated at 18 and 19, respectively. Part of the facing of the frame 17 is shown at 20, in Fig. 3, whereas the facing of the frame 16 is removed in said figure.

In that each frame 10 and 11 is of the same construction, the further detailed description of the frame with respect to leg members, braces and reinforcements will be described on the frame 10 and prime reference characters will be used on the frame 11.

At the ends of the frame 10 are sheet metal reinforcing plates 21—22 having an upstanding bearing portion 23—24 with which leg members 25—26 are pivoted by a pivot pin 27—28, which extends through the frame 16. The leg members lie flush within the frame in the collapsed position, as seen in Fig. 3. Hinged to the pivot end portions of the plates 21 and 22 are substantially triangular corner braces 29 and 30. This hinged construction is clearly shown, for example, in Fig. 4 of the drawing. The braces 29 and 30 have hook-shaped or L-shaped cleats 31 and 32 which are adapted to enter sockets 33 and 34 in the leg members, as clearly seen in Figs. 4 and 6 of the drawing.

Hinged to the pivot end of one of the leg members, the leg member 25 in the frame 16, is a transverse brace bar 35, the hinged connection being seen at 36. On the frame 17, the corresponding bar 35' is hinged to the leg member 26', as seen at 36'. At the free end of each brace bar 35—35' is an L-shaped cleat 37—37' which is adapted to enter a socket 38—38' of an opposed leg member, for example, the leg member 26 in the frame 16 and the leg member 25' in the frame 17. Pivoted to the leg members 26—25' respectively, are retaining straps or latches 39—39', one of which is clearly shown in Figs. 5 and 7 of the drawing.

Centrally of the frames 16 and 17 is a transverse channelled reinforcing plate 40—40' for bracing the central portions of these frames and also to form supports upon which the collapsed legs and brace members are free to rest.

When it is desired to convert the screen to a table, as shown in Fig. 2, the detachable facings,

as for example, the facing 20 on the frame 17, are removed, thus exposing one side of both frames 16 and 17. Then the legs 25-25' and 26-26' are swung into their operative position. The corner braces 28-30 and 29'-30' are moved into the position shown in Fig. 4, after which the brace bars 35-35' are swung downwardly and inwardly to provide the coupling engagement between the cleats 37-37' and the sockets of the opposed leg members, after which the latches 39-39' are swung into operative position and the table is now set-up and ready for use. It will be understood that the cross-braces 35-35' maintain and support the three sections of the screen in the table set-up position, as seen in Fig. 2.

In Figs. 8 and 9 of the drawing, I have shown a slight modification in which three screen sections 10', 11' and 12' are employed, the screens 10' and 12' being, generally speaking, identical with the sections 10 and 12, except for the differences later described. Whereas the section 11' differs from the section 11 in the positioning of the leg members and braces in the frame. In other words, instead of being disposed on the outer edge portion of the section 11', the leg members are disposed adjacent the inner hinged side of the frame and with this section, the detachable facing is disposed on a reverse side of the section so that the three sections 10', 11' and 12' can be collapsed to form a long, narrow table, in the manner clearly illustrated in Fig. 9 of the drawing.

Aside from positioning of the leg members and brace members, the structure of Figs. 8 and 9 is the same, except that the brace members 41-41' are substituted for the brace members 35-35' and differ therefrom to the extent of having recesses 42-42' formed therein to receive the inwardly folded screen section 11', as will clearly appear from a consideration of Fig. 9 of the drawing. For this reason, no further detailed description of the structure shown in Figs. 8 and 9 will be given, as the parts are duplicates of the structure, as specifically described in connection with the showing in Figs. 1 to 3 inclusive. The structure shown in Figs. 4, 5, 6 and 7 is applicable to the screen section 10', as well as the screen section 11', aside from the notching, or recessing of the brace members 41-41'.

From the foregoing, it will be apparent that my improved article of furniture may be quickly converted from a screen to a table and vice versa and, by reason of the structure employed, a strong and durable table is employed and the facings on the upper surface of the table, as seen in Fig. 2, and upper surfaces of the sections 10' and 12' as seen in Fig. 9, may be made of any suitable material to give the desired support and surface finish.

Having fully described my invention, what I claim as new and desire to secure by Letters Patent is:

1. A combination screen table device of the character described, said device comprising a plurality of hinged and collapsibly related rectangular sections of common size, end sections having, within boundaries thereof, leg members, means pivoting the leg members to outer corners of at least one of said end sections to swing into a position perpendicularly thereof, means for bracing each leg member when in extended position, means comprising a bar collapsible within each end section and movably coupled with a leg member in the section for bracing said leg member of said section with a leg member of an opposed end section, means retaining said bars in operative bracing position, and means for reinforcing said sections where the legs are pivoted thereto.

2. A combination screen table device of the character described, said device comprising a plurality of hinged and collapsibly related rectangular sections of common size, end sections having, within boundaries thereof, leg members, means pivoting the leg members to outer corners of at least one of said end sections to swing into a position perpendicularly thereof, means for bracing each leg member when in extended position, means comprising a bar collapsible within each end section and movably coupled with a leg member in the section for bracing said leg member of said section with a leg member of an opposed end section, means retaining said bars in operative bracing position, and means for reinforcing said sections where the legs are pivoted thereto.

3. A combination screen table device of the character described, said device comprising a plurality of hinged and collapsibly related rectangular sections of common size, end section having, within boundaries thereof, leg members, means pivoting the leg members to outer corners of at least one of said end sections to swing into a position perpendicularly thereof, means for bracing each leg member when in extended position, means comprising a bar collapsible within each end section and movably coupled with a leg member in the section for bracing said leg member of said section with a leg member of an opposed end section, means retaining said bars in operative bracing position, and means for reinforcing said sections where the legs are pivoted thereto, and means for reinforcing the center portion of each section.

4. A combination screen table device of the character described, said device comprising a plurality of hinged and collapsibly related rectangular sections of common size, end section having, within boundaries thereof, leg members, means pivoting the leg members to outer corners of at least one of said end sections to swing into a position perpendicularly thereof, means for bracing each leg member when in extended position, means comprising a bar collapsible within each end section and movably coupled with a leg member in the section for bracing said leg member of said section with a leg member of an opposed end section, means retaining said bars in operative bracing position, and the pivot of said leg members in both end sections being disposed at outer corner portions of both of said sections.

5. A combination screen table device of the character described, said device comprising a plurality of hinged and collapsibly related rectangular sections of common size, end sections having, within boundaries thereof, leg members, means pivoting the leg members to outer corners of at least one of said end sections to swing into a position perpendicularly thereof, means for bracing each leg member when in extended position, means comprising a bar collapsible within each end section and movably coupled with a leg member in the section for bracing said leg member of said section with a leg member of an opposed end section, means retaining said bars in operative bracing position, the pivots of the leg members in one section being disposed at outer corner portions thereof, and the pivots of the leg members in the other section being disposed at inner corner portions thereof.

6. An article of furniture of the character described, comprising a plurality of elongated rectangular sections hinged to form a screen-like body, said sections being of the same length and width, a pair of leg members pivotally mounted in corner portions of each of two of said sections, said leg members being normally collapsed within the boundaries of the sections, a corner brace collapsible within the section for bracing each leg member, a transverse brace element hingedly coupled with one leg member on each of said two sections and collapsible within said sections, said element being adapted to extend between and secured to a leg member of opposed leg sections, means reinforcing that part of each section with which the leg members are pivoted, and said cor-

ner braces being pivotally mounted on said reinforcing means.
